UNITED STATES PATENT OFFICE.

ALBERT K. PRATT, OF WHITINSVILLE, MASSACHUSETTS.

WARP STOP-MOTION FOR LOOMS.

SPECIFICATION forming part of Letters Patent No. 733,079, dated July 7, 1903.

Application filed May 8, 1901. Serial No. 59,283. (No model.)

To all whom it may concern:

Be it known that I, ALBERT K. PRATT, a citizen of the United States, residing at Whitinsville, in the county of Worcester and State of Massachusetts, have invented a new and useful Improvement in Warp Stop-Motions for Looms, of which the following is a specification.

This invention has reference to an improvement in mechanism controlled by detector-plates supported one on each warp-thread, by which on the breaking of a warp-thread the loom is automatically stopped.

The invention consists in the peculiar and novel construction of the actuating mechanism and the combination with the saw-blade feeler, whereby on the breaking of a warp-thread a detector-plate is dropped, the loom is stopped, and then the detector-plate is released automatically, as will be more fully set forth hereinafter.

Figure 1 is an end view of part of a loom, showing the warp stop-motion in connection with the coöperating parts of the loom. Fig. 2 is a rear view, on an enlarged scale, of one of the end frames, showing the connection of the warp stop-motion with the belt-shipper.

Similar marks of reference indicate corresponding parts in all the figures.

In the drawings, A indicates the end frame; B, the lay; C, the cam-shaft; D, the warp-beam; E, the warp-threads; F, the reciprocating feeler device, and G the detector-plates, supported each by a warp-thread. In the preferred form a feeler-blade f, provided with a saw-tooth edge, is reciprocated between two fixed saw-tooth blades f' f', in which the teeth are in the direction opposite to the direction of the teeth in the feeler-blades f, as is shown in Fig. 2, the construction being duplicated. The detector-plates G are arranged in two groups. Every alternate warp-thread is passed through the eyes of the detector-plates of one group and the intermediate warp-thread through the eyes of the detector-plates of the other group, as is shown in Fig. 1. On the breaking of a warp-thread the corresponding detector-plate drops down and enters the space between the saw-teeth of the stationary and moving feeler-blades, which will stop the movement of the latter and through the mechanism hereinafter described stop the running

of the loom. The two feeler-blades f are connected by a belt with the lever f², secured to one end of the rock-shaft f³. To the other end of the rock-shaft the lever f⁴ is secured. The lever f⁴ is connected by the link f⁵ to one end of the knock-off bar f⁶, the knock-off bar f⁶ being connected at the opposite end to the knock-off lever f¹⁵, which operates the shipper mechanism, and when in the raised position (shown in dotted lines in Fig. 1) may be operated by the lay as the lay approaches the end of its backward swing.

The rock-shaft f³ is supported in suitable bearings formed in brackets secured to the end frame and is held against longitudinal movement by collars. On the rock-shaft the lever f⁷ is adjustably secured, and this lever is connected with the arm f⁸ by the connecting-rod f⁹, adjustably secured in the slotted portion f¹⁰ of the arm f⁸. The arm f⁸ is pivoted at one end to the bracket f¹¹ and has the roller f¹², journaled in a curved arm. The roller bears on the cam c, by which at each rotation of the cam-shaft the arm f⁸ is raised against the tension of the coiled spring f¹³, one end of which is secured to the end frame and the other end to the arm f⁸.

The operating mechanism, so far as it has been described, acts to swing the arm f⁸ upward at each revolution of the cam-shaft and rock the rock-shaft, so as to draw out the feeler-blades f f and raise the knock-off bar f⁶ into the path of the knock-off f¹⁴ on the lay B. The cam c is placed on the cam-shaft in such a position that at every other pick the knock-off bar f⁶ is raised, while the lay swings through a portion of the rearward swing and is lowered before the knock-off on the lay encounters the shoulder on the knock-off bar. When, however, a warp-thread breaks, a detector-plate drops between the teeth of the fixed saw-tooth blades and a tooth on the feeler saw-blade, thereby locking the mechanism and arresting the knock-off arm in the raised position. In completing the backward movement of the lay the knock-off on the lay encounters the shoulder on the knock-off arm and drawing the same backward operates the knock-off and stops the loom.

The weight of the arm f⁸ and the parts connected with the knock-off arm f⁶, assisted by the tension of the coiled spring f¹³, act to

hold the detector-plate in the clamped position. These detector-plates are very thin and frail. They require to be raised to thread the warp-thread through them in mending 5 the broken warp and must be released. To overcome this objectionable feature, incident to most automatic warp stop-motions, I connect the actuating mechanism with some operative part of the loom, so that in the act of 10 stopping the loom the operative part may act to release the detector plate or plates.

In the modern loom the shipper-lever by which the loom is stopped and started is usually moved against a spring force in 15 starting the loom and is then secured in a notch in the holding-plate, and when released the spring acts to move the lever and operate the shipper to lead the belt from the tight pulley to the loose pulley, and so stop the 20 loom. In carrying out my invention I have selected moving parts of the belt-shipper and have connected them with the arm f^8 . As shown in Fig. 2, the chain d , having on one end the link d' , is connected on the other end 25 adjustably to the post d^2 , secured to the sleeve d^3 , sliding on the stud d^4 . The sleeve d^3 is part of the belt-shipper. A pin d^5 on the arm f^8 extends into the link d' . As the sleeve d^3 moves outward on the stud d^4 the chain d , 30 passing over a pulley d^8 , journaled on a bracket projecting from the frame, draws the link d' upward until the link engages with the pin d^5 and draws the arm f^8 upward sufficiently 35 to release, through the rock-shaft and the lever f^2 , the strain of the feeler saw-blade on the detector-plate.

I do not wish to confine myself to any particular construction of mechanism for connecting the feeler-actuating mechanism with 40 an operating part of the loom, as the same may be modified to best suit the construction of the loom.

Having thus described my invention, I claim as new and desire to secure by Letters 45 Patent—

1. In a warp stop-motion, the combination with the saw-tooth feeler of the detector mechanism, the lay, and a knock-off bar, of a rock-shaft, a lever on the rock-shaft for operating 50 the feeler and means on the rock-shaft for controlling the knock-off bar, a cam, and actuating mechanism intermediate the cam and the rock-shaft, as described.

2. A warp stop-motion having a detector 55 mechanism comprising a feeler, a rock-shaft for operating the same, a lever and cam for actuating the rock-shaft, a knock-off mechanism connected with the rock-shaft, in com-

bination with means connected with a moving part of the loom such as the belt-shipper and 60 the lever for actuating the rock-shaft for moving the feeler and releasing the drop wire after the knock-off mechanism has operated, as described.

3. In a warp stop-motion, the combination 65 of the following instrumentalities: detectors supported on the warp-threads, a feeler, mechanism for operating the feeler, means acting with the detectors for arresting the feeler when a warp-thread breaks, a knock- 70 off mechanism controlled by the feeler-operating mechanism, and reciprocating mechanism connected with the feeler-operating mechanism for loosening the clamping action of the feeler on the detectors, as described. 75

4. In a warp stop-motion the combination with detector-plates and feeler-blades, of mechanism for reciprocating the blades, a knock-off bar, a lay, means on the lay and bar for throwing the shipper, and means on 80 the frame including a stud and a sliding sleeve forming part of the belt-shipper and connections between the sleeve and the feeler-actuating means, substantially as described.

5. In a warp stop-motion for looms, the combination with detector-plates and feeler-blades, of means for actuating the feeler-blades, a shipper for the loom, a knock-off bar for releasing the shipper, means for actuating the knock-off bar, a stud on the loom-frame, 85 a sliding sleeve on the stud, and a flexible connection between the sleeve and the feeler-blade-actuating means, whereby the pressure of the feeler-blades on the detectors may be lessened before the machine is stopped, sub- 90 stantially as described.

6. In a warp stop-motion for looms, the combination with detector-plates and feeler-blades, of a knock-off bar and a shipper released thereby, means for operating the 100 knock-off bar, a rock-shaft for actuating the feeler-blades, a lever moving the rock-shaft, a cam for operating the lever, a stud on the loom-frame, a sliding sleeve forming part of the belt-shipper on the stud, and a chain connecting the sliding sleeve with the cam-operated lever whereby the feeler is operated to release the detector-plate, substantially as 105 described.

In testimony whereof I have signed my 110 name to this specification in the presence of two subscribing witnesses.

ALBERT K. PRATT.
